UNITED STATES PATENT OFFICE.

FRANZ BÜNDGENS, OF KIEL, GERMANY.

MINE-FINDER.

1,094,700.

Specification of Letters Patent. Patented Apr. 28, 1914.

Application filed December 27, 1911. Serial No. 668,189.

To all whom it may concern:

Be it known that I, FRANZ BÜNDGENS, manufacturer, a subject of the Emperor of Germany, residing at Sackgasse 7/9, Kiel, Germany, have invented certain new and useful Improvements in Mine-Finders, of which the following is a specification.

This invention relates to mine finders, and consists of a supporting buoy having a dragging weight and drag rope suspended thereto. Mine finders of this type are towed, as is well known, by a searching boat, while the drag rope attached to the dragging weight is led in the form of an arc to the dragging weight of a second similar device dragged by a second boat moving parallel to the first. There is also a device provided, which, upon engagement of the drag line with mine anchor rope, breaks the same and releases the mine from its anchorage.

In my present construction one of the dragging weights has suspended thereto the drag line and also a grapnel, which grapnel is subsequently used to break the anchor rope, as above noted. This drag line and grapnel suspending means comprises a spring slip coupling which opens under a predetermined tension of the drag line when it engages with a mine anchor rope. The drag line or the grapnel are not however completely released, but remain attached to the dragging weight by means of a line which unwinds from a drum attached in the said dragging weight, the said line being of such length that it enables the grapnel to be brought up to the anchor rope.

The grapnel and the end of the drag line, after they are released by the dragging weight, are supported by a grapnel supporting buoy which is detachably suspended to the main supporting buoy and does not become operative until the drag line and the grapnel have been released by the dragging weight, as the cable connecting it to the grapnel is of a corresponding length. The drag line at its other end, is connected to the dragging weight of a supporting line towed by a second boat. During the continuation of the travel, the end of the drag line with the grapnel will therefore be drawn against the anchor rope. After a certain tension is reached, the grapnel supporting buoy will become disconnected from the main supporting buoy, for instance owing to the opening of spring slip coupling or to a spring plug being pulled out of the main

supporting buoy (a signaling device on the main supporting buoy being at the same time operated if desired) and will then support the grapnel. When the grapnel is brought right against the anchor-rope, and the explosive charge carried by the grapnel is detonated by the mutual pressure or in some other way, a cutting device on the grapnel is operated, and the mine anchor rope is destroyed.

The new mine finder is illustrated in the accompanying drawing in that position of the single parts relatively to each other, which they occupy during the movement of the searching boats, before a mine anchor rope is caught by the drag line.

Figure 1 is a side elevation of my device; Fig. 2 is a plan view; Fig. 3 is a side view of the dragging weight with a portion broken away; Fig. 4 is a front view of the dragging weight with a portion broken away to show the drum braking mechanism; Fig. 5 is a longitudinal sectional view of the dragging weight-supporting buoy; Fig. 6 is a sectional view of the buoy taken on the line A—B, Fig. 5; Fig. 7 is a longitudinal section of the grapnel; Fig. 8 is a plan view of the same; Fig. 9 is a sectional view of the grapnel, taken on the line A—B of Fig. 7; Fig. 10 is a cross sectional view of the grapnel taken on the line C—D of Fig. 7; Fig. 11 is a side elevation of an operative detail of the grapnel known as a slide-block; and Fig. 12 is a side view of the drag link cross-pin.

On the searching boats is arranged a winch of the usual type with two cable drums. Each cable drum can be operated separately. To one cable drum is secured the buoy line M, and to the other the dragging weight line N. The buoy line M is connected to the supporting buoy A, and the dragging weight line N to the dragging weight D which is further supported by the supporting buoy A by means of a cable K.

The drag line H, and, by means of a short connecting piece of rope L, the grapnel G, are attached by means of shackles to a spring slip coupling mounted on the dragging weight. The grapnel G is connected in front by means of a short piece of rope J to the drag line H or is hooked to it by means of a shackle. Another connection of the supporting buoy A to the grapnel G is effected by means of the line O with the insertion of a small grapnel supporting buoy

C, said buoy being detachably connected to the larger buoy A by any suitable means, preferably a short cable S¹. Cable P is also suitably connected between grapnel G and the dragging weight D, this cable being suitably attached to the cable L at one end, the other end being attached to and wound upon a rotatable drum 14 concealed in the interior of the said dragging weight D. The dragging weight cable K and the line O must be in proper proportional length to each other.

While one section of the finder for one boat, shown in Fig. 1, consists of the supporting buoy A (preferably with a signal lamp) the dragging weight D with the spring slip coupling and inner cable drum, and grapnel G with line O, and the grapnel buoy C, the other section for the boat comprises only an ordinary supporting buoy without a signal lamp, a dragging weight D without a slip coupling, an inner cable drum, grapnel and line O with the grapnel buoy C. The two portions are connected together by the drag line H of suitable length.

A construction of the dragging weight D is shown in Figs. 3 and 4. It consists in the usual heavy metal block of rounding form, for the purpose of reducing as much as possible its resistance to movement in water, and is provided with lugs 1 for securing the cable K from the supporting buoy, and with lugs or eyes 2 and 3 for securing the drag line with its two branches.

At a suitable point on the dragging weight there is provided a recess 4 used for securing the slip coupling. The latter consists of the two levers 5 and 6 rotatably mounted about a pin 7 on a rod 8, the projections 9 being in the position of rest on the head of a sleeve 10 which is secured to the body of the dragging weight. In this manner the jaw of the coupling is held closed. The rod 8 is provided at the rear end with an abutment 11 against which presses a spring 12. If a tension of a given amount is exercised on the link or shackle placed in the jaws of the coupling the spring will yield, the projections 9 will slide away over the head of the sleeve 10, and the jaws of the coupling can open. The body of the dragging weight is moreover provided with a recess 13 in which is arranged a cable drum 14. On the latter is wound the line P leading to the grapnel. This line P prevents the complete release or control of the grapnel to which it is attached, when the drag line H, to which the grapnel is also attached, strikes the mine anchor rope, thereby causing the short towing cables P and L to be released. This line is also of such a length that it enables the grapnel to be brought to the mine anchor rope by the unwinding of the said line P from the cable drum 14 in the dragging

weight D. This function will be described hereinafter more in detail. An excessively rapid rotation of the drum is prevented by a brake 15 which, under the action of a spring 16, presses against a flange of the 70 drum.

Figs. 5 and 6 show in longitudinal and cross-section respectively, my preferred form of construction of the supporting buoy and signal device. The body 101, of the 75 supporting buoy A, which is dragged by the searching boat by means of a cable secured to an eye or lug 102, is provided with a ballast weight 103, for the purpose of keeping the buoy upright in water. On the upper 80 surface of the body thereof is arranged an electric incandescent lamp 104 protected by a bell and supplied with current from a battery 105 by means of wires 106 and 107. In the position of rest, the circuit is held open 85 by two springs 108 and 109 which are connected to the wires 106 and 107, and which are held apart from each other by means of an insulated separator 110 removably mounted between them. When the separator 110 90 is removed, the springs come together and close the circuit. The separator 110 is mounted on a plug 111 indicated by S in Fig. 1 and is inserted by friction into a sleeve 112 screwed into the rear wall of the 95 body of the buoy, and is provided with an eye-bar 113. Additionally the eye-bar may be further secured by a cross-pin 114, which passes through the said eye-bar and the sleeve 112. In the eye-bar 113 is secured a 100 line S² connected to the line O secured to the grapnel G, or to the grapnel buoy C. If the said lines are stretched by the grapnel being strained against a mine anchor rope the pin 114 is sheared through and the plug 111 105 pulled out at a given moment from the supporting buoy, and the circuit closed thereby causing the lamp to light. The crew will then be able to see that the explosion of the anchor rope is about to take place and can 110 take precautionary measures.

The body of the grapnel consists of two substantially semi-cylindrical halves a and b, with which the grapnel arms or flukes proper a' and b' are made in one piece. Between the halves a and b are inserted angular ledges c and d which, together with the halves inclose a cylindrical hollow space. The parts a b c d are held together by means of bolts e. While these bolts press the half a by means of nuts against the ledges e d, the half b is pivoted to them by means of the bolts f and g. The bolt f is permanently secured to the half b, while the bolt g is removable. The grapnel body can be then 120 opened upward, and the explosive cartridge h introduced. The short line J (Fig. 1) attached to the drag line H, is secured to a clamp i. The latter branches off like a fork 125 into two prongs i' i'' and is introduced into 130

the bores c' and d' formed in ledges c and d . The end of the prongs are provided with recesses i^3 i^4 (Fig. 12). Pawls K^1 and K^2 , which are pivotally mounted at l^1 and l^2 respectively, engage with their outer ends in the said recesses i^3 and i^4 , and thereby act as an interlock, to maintain the said clamp i in operative or neutral dragging position, and are in engagement at their inner ends with cam slots m' and m^2 of an adjustable slide block m . The latter projects through a guide sleeve o secured to the bottom n , and is prevented from shifting in sleeve o by a cross-pin p . In order to avoid destruction 5 of the pin before the apparatus is brought into the water, there is placed over the projecting end of the slide block m a protective cap q which is again removed on bringing it into water. At its other end, the slide block 10 m is screwed into a plate r against which rests the bottom of the explosive cartridge h . The plate r has oppositely arranged thereon two notches r^1 and r^2 which engage the two keel-like ledges c and d , respectively, 15 in such a manner as to prevent the rotation of said plate, and to permit of endwise movement relatively to the grapnel body. The plate, and method of engagement of the same with the member c and d , are indicated 20 in dotted lines in Fig. 10 at r , r^1 and r^2 .

When the grapnel strikes the anchor cable or rope of a mine the grapnel arms a' and b' guide it in such manner that it must lie in front on the explosive cartridge h . The explosive cartridge is consequently forced 35 backward, while the dragging fork i pulls the grapnel body forward. Forces then become operative which shear the cross-pin p . The cartridge h , the bottom r and the slide 40 block m can then slide back against the grapnel body, the catches k' and k^2 are turned by the cam slots m' m^2 and release the fork i , so that the latter is pulled out from the grapnel body by the drag line H or the line J .

Owing to the movement of the fork i relatively to the grapnel body, the cartridge h is ignited in the following manner: On the clamp fork i are mounted two metal sheets s which leave between them a hollow space 50 into which projects a friction ignition device or primer of the cartridge h , so that it is protected. Through the sheets or plates s is passed a pin t to which the friction ignition wire u is connected by means of a loop. 55 When the fork i slides out of the grapnel body the ignition wire is withdrawn from the cartridge by means of the pin t , whereupon the cartridge explodes.

The procedure during the searching for 60 mines anchored below the surface of the water, is as follows: After the finder has been arranged as shown in the drawing, the two towing boats move simultaneously, keeping as nearly as possible the same distance apart. The length of the connecting

line H determines the greatest lateral distance of the boats from each other. If a mine is anchored in the water in which the boats travel, the mine must be caught by the said line as the said drag line H establishes 70 connection between the two portions of the finder device. The drag line H is then stretched taut by the dragging weight lines, and as soon as a given tension is reached in the lines, the drag line H , and with it the 75 grapnel G with the short cables J and L are slipped by the spring slip coupling F arranged on the dragging weight. The grapnel G and the drag line H are then free from any fixed connection with the dragging 80 weight. In the interior of the dragging weight D there is however wound on a drum, a thin line P , the grapnel line, which is hooked with the end projecting from the dragging weight D , to the cable L of the 85 grapnel G . During further movement of the boats, the drag line H must be drawn around the anchored mine in such a manner that the end of the drag line, released by the dragging weight, and consequently also the 90 grapnel, are pulled against the anchor rope. The grapnel line P is unwound during that time from the drum in the dragging weight, and the line C with the grapnel buoy C and the connecting cable L , will become taut. 95 The grapnel line P is prevented from rapid unwinding by means of a friction brake 15, which bears against one side of the drum 14.

When the tension in the line O has reached a certain value, the plug S held fast in the supporting buoy 101 by means of a cross-pin 114, is pulled out. The pulling out of the plug S produces in the interior of the supporting buoy a contact which lights an incandescent light 104 arranged on the supporting buoy. The current for the incandescent lamp 104 is supplied by a battery 105 arranged in the interior of the supporting buoy. The lighting of the signal lamp 104 is the sign for those on board that the grapnel is being pulled against an anchored mine. When the grapnel has reached it, the anchor rope engages between the grapnel arms or flukes and if the boats continue to move, the ignition mechanism of the grapnel is released, the cartridge is detonated and breaks the anchoring. 110

What I claim as my invention, and desire to secure by Letters Patent is:—

1. In a mine finder, a buoy, a drag weight suspended from said buoy, a drag line attached at one end to said weight and suitably towed at its other end, means for automatically releasing said drag line from said weight when the tension between the said line and weight exceeds a predetermined minimum, an explosive-carrying grapnel secured to said drag line near said weight, automatic means for firing said explosive on striking an obstruction, a float adapted to 120
2. In a mine finder, a buoy, a drag weight suspended from said buoy, a drag line attached at one end to said weight and suitably towed at its other end, means for automatically releasing said drag line from said weight when the tension between the said line and weight exceeds a predetermined minimum, an explosive-carrying grapnel secured to said drag line near said weight, automatic means for firing said explosive on striking an obstruction, a float adapted to 125
3. In a mine finder, a buoy, a drag weight suspended from said buoy, a drag line attached at one end to said weight and suitably towed at its other end, means for automatically releasing said drag line from said weight when the tension between the said line and weight exceeds a predetermined minimum, an explosive-carrying grapnel secured to said drag line near said weight, automatic means for firing said explosive on striking an obstruction, a float adapted to 130

support said grapnel and detachably secured to the buoy, and a line secured to said grapnel and wound on a drum mounted within the drag weight.

5 2. In a mine finder, a buoy, a drag weight suspended from said buoy, a drag line attached at one end of said weight and suitably towed at its other end, means for automatically releasing said drag line from said 10 weight when the tension between the said line and weight exceeds a predetermined minimum, an explosive-carrying grapnel secured to said drag line near said weight, automatic means for firing said explosive on 15 striking an obstruction, a float adapted to support said grapnel and detachably secured to the buoy, a line secured to said grapnel and wound on a drum mounted within the drag weight, a signal device on said buoy, 20 and means on said buoy for operating said signal device upon detachment of said float whereby contact with a resisting object is indicated.

3. In a mine finder, a buoy, a drag weight 25 suspended from said buoy, a drag line attached at one end to said weight and suitably towed at its other end, means for automatically releasing said drag line from said weight when the tension between the said 30 line and weight exceeds a predetermined minimum, an explosive-carrying grapnel secured to said drag line near said weight, automatic means for firing said explosive on striking an obstruction, a float adapted to 35 support said grapnel and detachably secured to the buoy, a line secured to said grapnel and wound on a drum mounted within the drag weight, a signal device on said float consisting of an electric lamp, batteries carried by said float to supply current to said 40 lamp, a normally open circuit between said lamp and said batteries, and a detachable plug switch for said circuit, said switch comprising a securing means for said float 45 and normally holding said circuit open, whereby when said float is detached and the plug withdrawn the circuit between said lamp and said batteries is closed, thereby 50 operating the lamp.

4. The combination in a mine finder and 55 destroyer, of a drag weight, a float therefor, attaching means for supporting said drag weight from said float, a drag line at one end of said weight and a line to permit suitable towing at its other end, an explosively charged grapnel secured to said drag line near said weight, the other end of said grapnel being affixed to said weight, means for automatically releasing said grapnel from 60 said weight when the tension of said drag line exceeds a predetermined amount, automatic means for operating to fire the explosive charge in said grapnel upon obstruction of said drag line, a grapnel supporting float 65 detachably supported to said buoy, a signal

on said buoy normally held inoperative by said grapnel float attachment and operated by the detachment of said float upon the release of said grapnel from said weight, and controlling means between said grapnel and said weight to permit advancing of said buoy and weight out of the explosive zone, and to maintain said controlling connection with the grapnel until the instant of firing. 70

5. The combination in a mine finder and 75 destroyer, of a drag weight, a float therefor, attaching means for supporting said drag weight from said float, a drag line at one end of said weight and a line to permit suitable towing at its other end, an explosively 80 charged grapnel secured to said drag line near said weight, the other end of said grapnel being affixed to said weight, means for automatically releasing said grapnel from said weight when the tension of said drag line 85 exceeds a predetermined amount, automatic means for operating to fire the explosive charge in said grapnel upon obstruction of said drag line, a grapnel supporting float 90 detachably supported to said buoy, a signal on said buoy normally held inoperative by said grapnel float attachment and operated by the detachment of said float upon the release of said grapnel and said weight to permit advancing of said buoy and weight 95 out of the explosive zone, and to maintain said controlling connection with the grapnel until the instant of firing, said controlling means consisting of a clip coupling on said weight and being connected by a cable to 100 said grapnel and a rotatable cable drum carried by the said weight.

6. The combination in a mine finder and 105 destroyer, of a drag weight, a float therefor, attaching means for supporting said drag weight from said float, a drag line at one end of said weight and a line to permit suitable towing at its other end, an explosively charged grapnel secured to said drag line near said weight, the other end of said grapnel being affixed to said weight, means for automatically releasing said grapnel from said weight when the tension of said drag line exceeds a predetermined amount, automatic means for operating to fire the explosive charge in said grapnel upon obstruction of 110 said drag line, a grapnel supporting float detachably supported to said buoy, a signal on said buoy normally held inoperative by said grapnel float attachment and operated by the detachment of said float upon the release of said grapnel from said weight, and controlling means between said grapnel and said weight to permit advancing of said buoy and weight out of the explosive zone, 115 and to maintain said controlling connection with the grapnel until the instant of firing, said controlling means comprising a spring-actuated two-jawed slip coupling and a rotatable drum carried by said weight, an 120 125 130

eye-bar carried by said grapnel, a cable between said eye-bar, said drum, and said coupling, the said jaws of the slip coupling being pivotally mounted upon a longitudinally movable rod supported in operable position in a bushing in said weight and having rearwardly extending projections, said projections holding said jaws in operative cable-holding position by a sliding engagement with an extension on said weight, a spring on said rod arranged to maintain said jaws in operative cable-retaining position under a predetermined tension and to release said cable when the tension is exceeded, thereby permitting the said grapnel to be drawn to the obstruction encountered and causing the said drum to unwind the cable proportionately.

7. The combination in a mine finder and destroyer, of a drag weight, a float therefor, attaching means for supporting said drag weight from said float, a drag line at one end of said weight and a line to permit suitable towing at the other end, an explosively charged grapnel secured to said drag line near said weight, the other end of said grapnel being affixed to said weight when the tension of said drag line exceeds a predetermined amount, automatic means for operating to fire the explosive charge in said grapnel upon obstruction of said drag line, a grapnel supporting float detachably supported to said buoy, a signal on said buoy normally held inoperative by said grapnel float attachment and operated by the detachment of said float upon the release of said grapnel from said weight, and controlling means between said grapnel and said weight to permit advancing of said buoy and weight out of the explosive zone, and to maintain said controlling connection with the grapnel until the instant of firing, said grapnel comprising a pair of semi-cylindrical half frames having flukes thereon, a pair of ledge members oppositely arranged thereon between said frames and secured thereto by bolts, and forming a hollow space interiorly therein, a primed explosive in said space contained in a shell member, means to releasably hold said shell in inoperative position, and means in connection with said shell member and said tow line to operate to release said shell for longitudinal movement and detonate said explosive.

8. The combination in a mine finder and destroyer, of a drag weight, a float therefor, attaching means for supporting said drag weight from said float, a drag line at one end of said weight and a line to permit suitable towing at its other end, an explosively

charged grapnel secured to said drag line near said weight, the other end of said grapnel being affixed to said weight, means for automatically releasing said grapnel from said weight when the tension of said drag line exceeds a predetermined amount, automatic means for operating to fire the explosive charge in said grapnel upon obstruction of said drag line, a grapnel supporting float detachably supported to said buoy, a signal on said buoy normally held inoperative by said grapnel float attachment and operated by the detachment of said float upon the release of said grapnel from said weight, and controlling means between said grapnel and said weight to permit advancing of said buoy and weight out of the explosive zone, and to maintain said controlling connection with the grapnel until the instant of firing, 75 said grapnel comprising a pair of semi-cylindrical half frames having flukes thereon, a pair of ledge members oppositely arranged thereon between said frames and secured thereto by bolts, and forming a hollow space interiorly therein, a primed explosive in 80 said space contained in a shell member, means to releasably hold said shell in inoperative position, and means in connection with said shell member and said tow line to operate to release said shell for longitudinal 85 movement and detonate said explosive.

9. The combination with a pair of boats and a drag line therebetween, of a drag weight, a float attached to said drag weight, an explosive grapnel attached to said weight, and means for causing the explosion of said grapnel upon contact of the said drag line with an obstruction.

10. The combination with a pair of boats and a drag line therebetween of a drag weight, a signal carrying float attached to said drag weight, an explosive grapnel attached to said weight, means for causing the explosion of said grapnel upon contact of the said drag line with an obstruction, and means carried between said grapnel and said float to operate said signal to indicate the obstruction-contact of said drag line.

In witness whereof I have hereunto signed my name this 14th day of December 1911 105 in the presence of two subscribing witnesses.

FRANZ BÜNDGENS.
